DESIGN FOR A PIPE REST OR SIMILAR ARTICLE

Edward A. Kline, Jr., Great Barrington, Mass.

Application February 7, 1940, Serial No. 90,105

Term of patent 3½ years

To all whom it may concern:

Be it known that I, Edward A. Kline, Jr., a citizen of the United States, residing at Great Barrington, in the county of Berkshire and State of Massachusetts, have invented a new, original, and ornamental Design for a Pipe Rest or Similar Article, of which the following is a specification, reference being had to the accompanying drawing, forming part thereof.

Fig. 1 is a perspective view of a pipe rest, showing my new design; and

Fig. 2 is a side elevational view of the same.

I claim:

The ornamental design for a pipe rest or similar article, as shown.

EDWARD A. KLINE, JR.
